BIRD FEEDER

George F. Motter III, 3106 Lehigh St.,
Allentown, Pa. 18103

Filed July 3, 1972, Ser. No. 268,528

Term of patent 7 years

Int. Cl. D30—03

U.S. Cl. D30—14

Fig. 3

Fig. 4

FIG. 1 is a perspective view of a bird feeder, showing one form of my new design;

FIG. 2 is a bottom rear perspective view of the form shown in FIG. 1;

FIG. 3 is a top front perspective view of a bird feeder, showing another form of my new design; and

FIG. 4 is a bottom rear perspective view of the form shown in FIG. 3.

A portion of the stake has been broken away and omitted in FIGS. 1 and 2 to show indeterminate length.

I claim:

The ornamental design for a bird feeder, as shown and described.
